RAILING

Edward J. Kusel, 2343 Ridgewood Road, and Robert S. Mankin, 1954 Stockbridge Road, both of Akron, Ohio 44319

Continuation of design applications Ser. No. 849 and Ser. No. 858, Feb. 1, 1966. This application Feb. 13, 1967, Ser. No. 8,195

Term of patent 14 years

(Cl. D13—7)

FIGURE 1 is a perspective view of a railing embodying our new design and partially broken away to indicate an article of undetermined length.

FIGURE 2 is a perspective view of the railing of FIGURE 1 in a different position.

FIGURE 3 is a cross sectional view of the railing taken on the lines 3-3 of FIGURE 1.

FIGURE 4 is a perspective view of a modified form of a railing embodying our new design and partially broken away to indicate an article of undetermined length.

FIGURE 5 is a perspective view of the railing of FIGURE 4 in a different position.

FIGURE 6 is a cross sectional view of the railing taken on the lines 6-6 of FIGURE 4.

The dominant features of the railing design reside in the portions shown in full lines. The step construction shown in broken lines in FIGURES 2 and 5 is disclosed for illustrative purposes only.

This application is a continuation of applicants' earlier co-pending applications Ser. No. D. 858 filed Feb. 1, 1966 and Ser. No. D. 849 filed Feb. 1, 1966 and now abandoned.

We claim:

The ornamental design for a railing, as shown and described.
